WINDOW SCREEN

Eric Sigfrid Persson, Malmo, Sweden

Application April 5, 1940, Serial No. 328,112

5 Claims. (Cl. 156—14)

My present invention relates to a screen for windows of the type comprising a sash mounted to pivot in a frame so as to form, in opened condition, at least one rectangular opening and at least two triangular openings between the frame and sash.

The object of my invention is to provide a very simple and inexpensive screen of the kind indicated which effectively covers all the openings but does not prevent the free view through the window glass.

Another object of my invention is to provide a screen of the kind indicated which is readily inserted and removed.

15 A further object of my invention is to provide a screen which can be used with the same effect with a number of different openings of the window.

Some embodiments of my invention are illustrated, for the purpose of explanation, in the drawing, in which:

Fig. 1 shows a partial perspective view of one embodiment of the screen,

Fig. 2 shows a partial sectional plan view of the same attached to a window,

Fig. 3 shows a plan view of the screen with the side members tilted down,

Fig. 4 shows an elevation of the same,

Fig. 5 shows a plan view of another embodiment of my invention,

Fig. 6 shows a partial plan view to an enlarged scale of the same attached to a window,

Fig. 7 shows diagrammatically the arrangement of the screen in a window of the type having a sash mounted in a frame so as to pivot about an axis at about the middle of the height of said sash, and

Figs. 8 and 9 are detail views.

In the embodiment shown in Figs. 1 to 4, inclusive, the screen comprises a bottom member 1 and two side members 2, 3 for covering the rectangular opening and the two triangular openings, respectively. The window frame is indicated by 4 and the window sash by 5. The side members 2, 3 of the screen are connected with the bottom member 1 by means of hinges 6 and 7, respectively.

The screen is secured to the sash 5, for instance by means of turnable heads 8 connected to the sash and coacting with elongated holes 9 in a flange 10 on the screen member 2. Said heads 8 are of an elongated shape and rather narrow, so as to pass readily through the holes 9 when turned to a corresponding position, where-

as they lock the screen to the sash, when turned to any other position.

At the inner edge, said side screen member 2 is provided with a flange 11 projecting in a direction opposite to the flange 10 and serving as an abutment and tightening means between the screen member 2 and the sash. The screen member has, of course, a similar flange, and preferably also the bottom member 1 is provided with a flange 12 of the same kind and for similar 10 and other purposes.

In order to ensure sufficient degree of tightness between the screen and the frame also in case the window sash is not opened enough to establish engagement between the frame 4 and the 15 flanges 11, 12, cords 13 of rubber or similar material are provided on the outside of the screen members, as indicated in the drawing. Of course, tightening means for the same purpose can be arranged also in other ways as, for instance, by fastening rubber strips 14 by means of clips or clamping means 15, as indicated in Fig. 9.

The dotted lines in Fig. 4 indicate how the screen can be folded together by moving the side members 2, 3 towards each other. In a window 25 pivoted at about the middle of its height there will form two rectangular and four triangular openings, and the screen will assume the general appearance illustrated diagrammatically in Fig. 7.

In the embodiment of my invention illustrated 30 in Figs. 5 and 6, the screen comprises two units, each of the same general design as the screen described above. Thus, there is one unit A comprising a bottom member 20 and two side members 21, 22 connected with the bottom member 35 20 by means of hinges 23 and 24, respectively. Another unit B comprises a bottom member 25 and two side members 26, 27 connected to the bottom member 25 by means of hinges 28 and 29, respectively.

The unit B is somewhat smaller than the unit A so that it can be mounted within said unit A, as shown in Fig. 6. The unit B is detachably secured to the sash 5 in a similar way as described in connection with the embodiment of 45 Figs. 1 to 4, inclusive, i. e. by means of a flange 10 and fastening means 8 for coaction with holes in said flange. At the opposite edge a rubber strip 30 is mounted in a holder 31.

The other unit A is detachably fastened to 50 either the window frame or the sash at two points 32 and 33 (Fig. 5) only and is thus swingable about said two points. It is provided with two flanges 34 and 35 projecting in opposite directions, as shown in Fig. 6. Cords 13 of rubber or 55

similar material are provided in the same way and for the same purpose as in the embodiment of Figs. 1 and 2.

It should be obvious that, when the window is being opened, the screen unit B is participating in the movement of the sash 5, thus being moved upwards as seen in Fig. 6. Thereby the rubber strip 30 is sliding against the unit A, thus forming a tight joint therebetween.

10 10 When the window sash has been opened enough to make the holder 31 engage the flange 34, the unit A is forced to take part in the continued movement of said sash 5, the cords 13 thereby tightening the joint between the unit A and the frame 4, as indicated in Fig. 6. Finally the flange 35 engages the frame 4, the two screen units A and B then together covering the entire opening between the frame 4 and sash 5.

Several different modifications of the embodiments described can be made without departing from the scope of the invention. Thus, in some cases, it might be advisable or necessary to make the bottom parts of the screen curved as seen in cross-section instead of straight, as shown 20 in Fig. 1. Also in other respects modifications are feasible and, therefore, the embodiments described above must not in any way be interpreted as limitations of the scope of the invention but just as exemplifications.

30 30 It is also within the concept of the present invention to make the bottom members 1, 20 and 25 of variable width so that the screen can be used in windows of different widths. This may be accomplished by making the bottom members 35 1, 20 and 25 in two or more overlapping sections slidably connected to each other. One section of a bottom member formed of a plurality of sections may be telescopically slidably mounted in a second adjacent section by providing the second section with channel-like guides receiving the first section.

What I claim is:

1. In a window screen for covering the openings between frame and sash of a window having the sash mounted to turn in the frame so as to form, in opened position, at least one rectangular opening and at least two triangular openings between the frame and sash, a screen member for covering said rectangular opening, two other screen members for covering said triangular openings, and hinges connecting said two last mentioned screen members to said first-mentioned screen member.

2. In a window screen for covering the openings between frame and sash of a window having the sash mounted to turn in the frame so as to form, in opened position, at least one rectangular opening and at least two triangular openings between the frame and sash, a screen member for covering said rectangular opening, two other screen members for covering said triangular openings, hinges connecting said two last mentioned screen members to said first-mentioned screen member, and means for detachably securing said screen members at said openings.

3. In a window screen for covering the openings between frame and sash of a window having the sash mounted to turn in the frame so as to form, in opened position, at least one rectangular opening and at least two triangular openings between the frame and sash, a screen member for covering said rectangular opening, two other screen members for covering said triangular openings, hinges connecting said two last-mentioned screen members to said first-mentioned screen member, and means for tightening joints between the frame and the screen members in opened positions of the window sash.

4. In a window screen for covering the openings between frame and sash of a window having the sash mounted to turn in the frame so as to form, in opened position, at least one rectangular opening and at least two triangular openings between the frame and sash, a screen member for covering said rectangular opening, two other screen members for covering said triangular openings, hinges connecting said two last-mentioned screen members to said first-mentioned screen member, and rubber strips on the surfaces of the screen members facing the window frame for the purpose of tightening the joints between the frame and the screen members in opened positions of the window sash.

5. In a window screen for covering the openings between frame and sash of a window having the sash mounted to turn in the frame so as to form, in opened position, at least one rectangular opening and at least two triangular openings between the frame and sash, a number of screen units each comprising three screen members interconnected by hinges, said screen units fitting within each other, and means for tightening the joints between said screen units.

ERIC SIGFRID PERSSON.
